UNITED STATES PATENT OFFICE.

SALVATORE D. ROSE, OF SEATTLE, WASHINGTON.

ANNUNCIATOR-SETTING DEVICE.

Application filed July 31, 1920. Serial No. 400,342.

To all whom it may concern:

Be it known that I, SALVATORE D. Rose, a citizen of the United States, and resident of the city of Seattle, county of King, State 5 of Washington, have invented certain new and useful Improvements in Annunciator-Setting Devices, of which the following is a specification.

This invention relates to improvements 10 in annunciators, and more particularly to annunciator setting mechanism whereby the lift rods, used in the usual type of electrically operated annunciators for moving the station designation pointers or blocks 15 from released to set position, may be actuated to set the released pointers.

The principal object of the present invention is to provide a device of the above character that may be attached, or applied 20 to annunciators of the most common types without necessitating alteration in their construction, and which by its use will save time and energy of an operator, especially where such annunciators are used 25 in passenger elevators.

Another object of the invention is to provide setting mechanism of the above character that may be operated both electrically on the closing of an electric circuit 30 through a magnet, or may be operated manually.

A still further object is to provide a setting device which may be made and installed at a relatively small expense and 35 which will in no way interfere with the operation of the parts of an annunciator as they already exist.

In accomplishing these and other objects of the invention I have provided the improved details of construction, the preferred 40 forms of which are illustrated in the accompanying drawings, wherein—

Figure 1 is a partial view of an annunciator, equipped with setting mechanism embodied by the present invention.

Figure 2 is a side view of part of the annunciator mechanism.

Referring more in detail to the drawings—

50 1 designates the lower end of the housing of an annunciator which may be of the character now generally in use in passenger elevators, and which comprises a plurality of electrically controlled blocks or pointers 55 which are individually movable and when

moved to certain positions designate certain points of call where attention is required.

In the present device, the indicators comprise small blocks, or plates 2, which are pivotally supported by arms 3 and when 60 in set position are disposed above individual openings 4 in the front of the housing 1. Each block 2 is normally held in set position by a yieldable latch, not shown, which is adapted to be magnetically moved by the 65 closing of an electric circuit, through a magnet (not shown), by pressing a switch button at some point of call or station, to release the block so that it will fall to position in front of its respective opening 70 4 and can be seen by an operator.

These blocks are moved back to set position after being released by upward movement of a vertical rod 6 which is mounted slidably in the housing and has laterally 75 extended arms 7 which will liftingly engage the different arms 3 when the rod is moved upwardly.

Applicant has learned from experience that repeated re-setting of the signals in 80 elevator annunciators becomes very tiresome, especially where the operator has to reach or turn in order to have access to the setting rod. Also the operator's attention is often taken from the manipulation 85 of the elevator control lever by such reaching which makes accidents more apt to occur.

The present invention seeks therefore to overcome these apparent difficulties and disadvantages by a mechanism especially 90 adapted for use in elevator annunciators, which may be either electrically or manually actuated, without apparent effort and without detracting attention from the work of operating the elevator control lever.

The present device consists of a lever 10 that is pivotally mounted intermediate its ends by a pivot bolt, screw or pin 11, upon a bracket 12 which is mounted in any suitable manner upon a wall of the housing 1. 100 The lever 10 has its inner end disposed beneath the lower end of the lift rod 6 and mounted above the lever, between this end and the pivot pin 11, is a magnet 5 having a core 15 extended downwardly and terminating at a short distance above the lever. Circuit wires 16 and 17 are connected with the magnet coil through any suitable source of electricity, as indicated by the battery at 18, and connect with a circuit closing 110

switch button 19 which may be mounted on the lever 20 which is actuated to control movement of the elevator wherein the annunciator is used.

5 The wires 16 and 17 are suitably insulated and are attached to the outer end of the lever 10 and depend to an accessible position adjacent the control lever where they may be equipped with a ball or other suitable 10 handle 22 which may be easily grasped.

From the ball the wires are extended to the switch button 19 that is mounted on the control lever 25 of the elevator, and which is of the character that will cause a circuit 15 to be closed through the wires when pressed inwardly.

With the parts so constructed and assembled, the lever 10 may be actuated manually by a downward pull on the ball 22, 20 or it may be actuated electrically by closing an electric circuit through the magnet 5, by pressure on the switch button 19.

Either manner of actuation will cause the bar 6 to be lifted and the blocks 2 re-set. 25 after being released.

Such mechanism will save the time and energy of an elevator operator and will add safety to elevator operation.

It is apparent that various changes in the

shape of the lever, its mounting device, also 30 in the method of mounting the circuit closing button could be made without departing from the spirit of the invention, and I do not wish to limit the construction only to the details shown. 35

Having thus described my invention, what I claim as new therein and desire to secure by Letters-Patent, is:

In an annunciator of the character described, the combination with a vertically 40 shiftable signal setting rod thereof, of a lever pivotally supported between its ends with its inner end disposed beneath said rod, an electro-magnet mounted adjacent to and cooperating with said lever, electric circuit 45 wires for said magnet fixed to the outer end of the lever and depending therefrom, a switch connected with the lower ends of said wires, whereby a circuit may be closed through the magnet to cause the lever to be 50 magnetically lifted to actuate the signal setting rod and a handle member secured on said wires whereby said lever may be manually operated.

Signed at Seattle, Washington this 24th 55 day of July 1920.

SALVATORE D. ROSE.
